UNITED STATES PATENT OFFICE.

JOHN H. MCGINTY, OF MANSFIELD, OHIO, ASSIGNOR OF TWO-THIRDS TO
WILLIAM J. HOLWAY, ROBERT LOWE, AND FREDERICK MCKEE, OF
WASHINGTON, PENNSYLVANIA.

OIL-CAN.

SPECIFICATION forming part of Letters Patent No. 557,082, dated March 24, 1896.

Application filed September 25, 1895. Serial No. 563,573. (No model.)

To all whom it may concern:

Be it known that I, JOHN H. MCGINTY, a citizen of the United States, residing at Mansfield, in the county of Richland and State of Ohio, have invented certain new and useful Improvements in Oil-Can Spouts; and I do declare the following to be a full, clear, and exact description of the invention, such as will enable others skilled in the art to which it applies to make and use the same, reference being had to the accompanying drawing, and to the letters of reference marked thereon, which forms a part of this specification.

The invention relates to the spouts of oil-cans which are liable to get choked at the outlet; and the invention consists in the means employed to unchoke them.

The drawing is a vertical diametrical section of an oil-can, showing my improvements. In the drawing, A represents the can; B, its spout, tapered upwardly, while its bottom is provided with the exterior flange b; C, a spiral spring in a cage e of the hollow screw-stopper E, and D is the wire by which obstructions at the outlet b² may be ejected. This wire is fast in the bottom of the cage e, open at the sides, in which the spout B is movable up and down on the spring C, which

holds the flange b against an interior screw-shoulder a. By pressing down the fast spout-collar b' the wire D is projected at the top through the outlet b², so as to relieve it of any stoppage in a moment.

Having thus described all that is necessary to a full understanding of my invention, what I claim as new, and desire to protect by Letters Patent, is—

1. An oil-can having a spout with exterior flange at bottom, a screw-stopper with a cage e and having an interior shoulder against which the flange is held and a fixed central cleaning-wire fast to said cage and extending nearly to the top of spout as and for the purpose described.

2. In an oil-can, the combination of a screw-stopper with cage e, an oil-spout, a spring in the cage and a central wire fixed to the cage, the spout being movable up and down over the wire to clean out the end of spout as set forth.

In testimony whereof I affix my signature in presence of two witnesses.

JOHN H. MCGINTY.
